UNITED STATES PATENT OFFICE.

ANTON I. SANDBO, OF ROCK ISLAND, ILLINOIS.

SAFETY CRANKING DEVICE.

1,288,443.

Specification of Letters Patent. Patented Dec. 17, 1918.

Application filed May 17, 1918. Serial No. 235,117.

To all whom it may concern:

Be it known that I, ANTON I. SANDBO, a citizen of the United States, residing at Rock Island, in the county of Rock Island 5 and State of Illinois, have invented certain new and useful Improvements in Safety Cranking Devices; and I do hereby declare the following to be a full, clear, and exact description of the invention, such as will 10 enable others skilled in the art to which it appertains to make and use the same.

This invention relates to starting mechanism for the internal combustion engines of automobiles, motor boats and in fact any 15 engines of this class adapted to be manually started.

The primary object of the invention is to provide improved automatically operating safety mechanism for disengaging the starting crank from the shaft of the motor in the event of back firing of the motor, whereby 20 to prevent injury to the operator.

A further object of the invention is to simplify the construction and improve and 25 insure the practical operation of such mechanism when such back firing takes place, such back firing usually resulting from premature ignition in the cylinder of the engine.

With these objects in view the invention 30 consists in the improved construction, arrangement and combination of the parts of the mechanism of the character specified, which will be hereinafter fully described 35 and afterward specifically claimed.

In order that the construction and operation thereof may be readily comprehended, I have illustrated an approved embodiment 40 of my invention in the accompanying drawings, and will now proceed to fully describe the same in connection with said drawings, in which—

Figure 1 represents, in front end elevation, the starting crank and the adjacent 45 parts,

Fig. 2, a transverse, vertical, sectional view on the plane indicated by the broken line 2—2 of Fig. 3, looking in the direction of the arrow,

Fig. 3, mostly a view in side elevation

showing the parts from the end of the engine shaft to the crank, inclusive, the automobile spring and its case being shown in section,

Fig. 4, a view similar to Fig. 3, except 55 that all of the parts carried on the crank and its shaft are shown in section,

Fig. 5, a view, in side elevation, of the ring which carries the lugs for engaging in 60 the slots of the release cams,

Fig. 6, a view, in side elevation, of the drum which receives the ring of Fig. 5,

Fig. 7, a detail top plan view of the crank fastener,

Figs. 8 and 9, detail views of the release 65 cams or brackets, and

Fig. 10, a sectional view of a modified drum to be used on a straight shaft.

Like reference characters mark the same 70 parts in all of the figures of the drawing.

Referring specifically to the drawing, 12 indicates the end of the shaft of the motor having a diametrically projecting pin 13, which engages the teeth of the usual ratchet 14, secured by a pin 14^a to the end of the 75 shaft 15 of the starter, during the operation of starting the engine in the usual manner by turning the attached starter crank 16, the starter shaft 15 being normally pressed into position with relation to the engine shaft by 80 a spring 17 surrounding said shaft 15 the shaft being inclosed in a cylinder 18 against which one end of the spring inclosed in a sleeve 19, engages, while the other end presses against a ring 20 secured around the 85 shaft 15 to hold said shaft away from the engine shaft with the teeth of the ratchet 14 clear of and out of the line of the pin 13.

21 indicates the front cross bar of the chassis which is formed with open bottom 90 to receive a spring 22 which is held in the cross bar by the clamps 23 and nuts 24, 25.

The nuts 25 also clamp in position the release brackets 26 and 27, the stems 28 of the clamps 23 on which the nuts are threaded 95 passing through openings 29 in the horizontal flanges 30 of the brackets 26 and 27.

On the starter crank shaft 15 is a drum 31 (see Figs. 3, 4 and 10) secured by screws 32 to said shaft, and serving to receive 100

screws 33 by which the crank fastener 34 is held tight against the drum, the fastener having a curved wedging inner surface 35 which, when the screws 33 are tightened up 5 serves to bind these parts tightly to the crank shaft.

The drum 31 is surrounded by a ring 36, and has in its outer peripheral surface a series of cups 37, the ring having in its inner 10 surface substantially triangular shaped pockets 38 opposite said cups, a ball 39 being loosely placed in each of said pockets.

Any desired number of pockets may be used as at the left of Fig. 2, and the remainder of the drum recessed to reduce its 15 weight and balance the same, as at the right of said figure.

With this construction, when the crank is turned to the right, the balls will roll up 20 into the larger upper ends of the pockets and thereby release the drum and ring but in case the engine back fires, or for any other reason the crank is turned to the left, the balls will drop into the shallow ends of the 25 pockets and cause the drum and ring to turn together.

The release brackets 26 and 27 are provided with curved bodies 40 in which are 30 slots 41 in which are seated lugs 42 on the ring 36, so that when the ring is turned by back firing or otherwise to the left, these lugs will ride up on the inclined slits, and the ring and drum, with the crank shaft 15 and the ratchet 14 will be forced away from the engine shaft 12, causing the teeth of the 35 ratchet to be disengaged from the pin 13 on the engine shaft, so that the crank and its attached parts will not be carried around backward by the engine shaft.

The utility and simplicity of my invention 40 will be evident from the foregoing and I desire to be understood that changes and variations may be made from the specific construction described, without departing 45 from the spirit and scope of the invention.

Having thus fully described my invention, what I claim as new and desire to secure by Letters Patent of the United States is:—

1. The combination with the front bar of 50 the chassis and the crank shaft of a starter, of release brackets secured to the chassis bar and provided with inclined slots, a ring surrounding the crank shaft and provided with 55 lugs engaging in said slots, and means for releasing said engagement when the shaft is turned backward or to the left, as by back firing of the engine.

2. The combination with the front bar of 60 the chassis and the crank shaft of a starter, of release brackets secured to the chassis bar and provided with inclined slots, a ring surrounding the crank shaft and provided

with lugs engaging in said slots, and means for releasing said engagement when the 65 shaft is turned backward or to the left, as by back firing of the engine, said releasing means comprising a drum within the ring provided with exterior pockets in its periphery, interior triangular pockets in the ring, with 70 their narrow ends to the left, and balls which wedge down into said narrow ends causing the ring and drum to rotate together with the shaft thus forcing the lugs of the ring to travel in the inclined slots of 75 the release brackets and force the shaft rearwardly in case of back firing.

3. The combination with the engine shaft having a lateral pin, a starter crank shaft having a ratchet at its forward end, a spring 80 normally maintaining the ratchet in engagement with the pin to cause the engine shaft to be turned to the right when the starter crank is so turned, the chassis rear bar, release brackets secured to said bar and having 85 inclined grooves, a drum on the crank shaft, turning therewith, and having exterior peripheral pockets, a ring around the drum having triangular pockets narrowing to the left, lugs on the ring engaging in the slots of 90 the release brackets, and balls in the cups and pockets which remain in the wider parts of the pockets when the crank shaft is turned to the right and permits the drum to rotate with the shaft without carrying the ring 95 with it, the balls wedging into the narrow ends of the pockets when the shaft and drum are turned to the left carrying the ring and its lugs with it, thus withdrawing the starter shaft ratchet from engagement with the 100 pin of the engine shaft.

4. The combination with a starter crank shaft, of a drum secured thereon, and a crank fastener disposed upon said shaft to extend between the drum and shaft and secured to said drum. 105

5. The combination with a starter crank shaft, of a drum secured thereon, a crank fastener having a curved wedging inner surface disposed to extend between said drum 110 and shaft, and means for securing said fastener to said drum.

6. The combination with a support and an engine cranking shaft, of a bracket having an inclined slot, a lug projecting into said slot, one of said parts being mounted to rotate with the cranking shaft and disposed to impart an axial movement thereto and the other being stationary, and means for throwing the cranking shaft outwardly upon its 115 release.

7. The combination with a fixed support and an engine cranking shaft, of a ring surrounding the cranking shaft, clutch means interposed between said ring and cranking 125 shaft whereby the ring will rotate with the

cranking shaft in one direction, release
brackets each having an inclined slot, lugs
projecting into said inclined slots, one of
said two last named elements being station-
ary and the other movable disposed to im-
part an axial movement to said shaft.

In testimony whereof I have signed my

name to this specification in the presence of
two subscribing witnesses.

ANTON I. SANDBO.
